FOLDING FRAMED DISPLAY

Henry Ziemmerman, Chicago, Ill., assignor to
 Chicago Cardboard Company, Chicago, Ill., a
 corporation of Illinois

Application April 30, 1934, Serial No. 723,096

9 Claims. (Cl. 40—154)

This invention relates in general to a framed display preferably made entirely of one sheet of material such as cardboard with an attached supporting easel and has more particular reference 5 to the scoring and folding of a piece of sheet material to resemble a framed picture in which the frame is distinctively offset with respect to the picture plane.

An important object of the invention is in the 10 provision of a framed picture display in which the frame is foldable out of sheet material and the connection of the frame portions holds the frame in distended position.

A further object of the invention is in the 15 provision of improved means for attaching or connecting the frame portions to hold them in distended position.

A still further object of the invention is in the 20 provision of an easel mounting attached to the rear of the picture frame for holding it in upright position and collapsible against the back of the frame so that a number of frames will nest together and fold compactly for shipping and storing them in quantities.

25 Further objects of the invention will appear hereinafter, the accompanying drawings illustrating preferred structures and embodiments of the invention.

In the drawings, Fig. 1 is a front elevation of 30 a frame and easel constructed in accordance with the principles of this invention;

Fig. 2 illustrates a blank from which the frame is made and a portion of the easel blank;

Fig. 3 is a section taken on the line 3—3 of 35 Fig. 1;

Fig. 4 is an enlarged detail rear view of one corner of the folded frame showing one of the frame engaging means;

Fig. 5 is an enlarged sectional view of the frame 40 engaging parts as shown at the top of Fig. 3;

Fig. 6 is an enlarged detail of one corner of the 45 interengaging frame structure;

Figs. 7 and 8 are front and rear views respectively of a modified frame structure and the 50 supporting easels;

Fig. 9 is a section taken on the line 9—9 of Fig. 7;

Fig. 10 illustrates the blank structure and 55 method of folding of the modification shown in Figs. 7, 8 and 9;

Fig. 11 illustrates another frame structure more 60 similar to that of Fig. 1;

Fig. 12 is a section taken on the line 12—12 of Fig. 11; and

Fig. 13 is a sectional view illustrating the nest- 65

ing of a number of folding frames like that of Fig. 1 with folding easels like that of Figs. 8 and 9 attached thereto.

In producing a representation of a picture frame for a complete display from a single sheet 5 of material it is necessary to cut the marginal edge producing the frame in order that the frame will be offset from the plane of the picture within it to produce the simulation of a completely framed picture. The present invention provides 10 for the cutting and scoring of the marginal edge of a sheet of flexible material such as cardboard and the like, so that in bringing or connecting transversely cut portions of the rim together it will be folded to represent a marginal frame and 15 may be upheld by an inclined easel representing a framed picture as a novel display for advertising and exhibiting purposes.

Referring now more particularly to the drawings, a single sheet of material 1, as represented 20 more clearly in Fig. 2, is cut and scored about the edges to provide connected side frame 2 and end portions 3 by means of front and rear score lines 4 and 5, and at the ends are locking flaps 6 formed by transverse cuts 7 in the marginal edge 25 and having parallel score lines 4 and 5 to fold them in conformity with the remainder of the frame. At the ends of the locking flaps 6 and extending from the corners of the picture plane surface 8 are angular projections 9 which extend outside of the score line 5 defining the inner edge 30 of the picture surface 8. These angular portions 9 are cut from the sheet blank 1 and cause the frame end portions 3 to be inclined outwardly in the blank 1 and the end portions 3 are cut to 35 make an interengaging hooked portion with the upper edge of the locking flaps 6 comprising a locking tongue 10 extending from an angular locking wing 11 formed by a score line 12 extending from the marginal edge to the edge of the 40 score line 4 in the flap 6 and an angular notch 13 in the upper marginal corner of the frame extension 3 as shown more clearly in Fig. 6.

With this construction there is little waste material as the parts are cut solidly from the 45 blank 1 as shown more clearly in Fig. 6. In order to fold up the frame surrounding the picture surface 8, the angular corners of the margins must be provided with a double or heavy crease line 14 about which the frame portions 2 and 3 50 will fold in opposite directions from the corner juncture of the score lines 4. This permits the marginal frame portions on opposite sides of the score lines 4 to be folded angularly to each other and also at an angle to the picture plane 8 and

by such folding the end portions 3 of the frame are moved at right angles to the sides 2 and the locking flap 6 is correspondingly folded on its fold lines 4 and 5 so that the locking tongue 10 5 may be engaged with the locking notch 13 in order to hold the frame portions together and by similar engagement on both ends of the locking flaps 6 the entire frame is locked together in rectangular relation about the edge of the picture 10 surface 8. The locking wings 11 angularly offset the locking flap 6 in advance of the remainder 15 of the frame at the top and bottom for added decorative effect and to provide a space for a name plate or an advertising label at the top and 15 bottom of the frame.

In order to hold the frame portions in proper alignment, the end portions 3 are separated from the angular projecting portions 9 by a slit 15 which extends to the adjacent inner corner of 20 the frame so that the portion 16' included between the slit 15 and the score line 4 may be placed in front of the angular projecting portion 9 before the frame is locked in its rectangular position. The object of this is to hold this portion 16' in alignment with that portion of the locking flap which is included between the score 25 lines 4 and 5, and to make this angular portion of the frame appear as a substantial continuation thereof.

30 The extremities of adjacent angular projections 9 may be provided with perforations 16 at the upper ends thereof through which a cord 17 may be inserted, as shown in Fig. 4, at the rear of the frame, so that it may be hung instead 35 of supported by an easel as hereafter set forth.

Any suitable easel may be provided for supporting the frame in upright or slightly inclined position and a one-piece easel, as shown by Figs. 2 and 3 comprises a strip of pasteboard or other 40 suitable sheet material having continuous back, base, and front sections with a pasting flange 20 at its upper end secured to the back of the picture frame near the top. Extending from the attached flange 20 is a hinged back stay 21 with 45 lateral stiffening wings 22, the upper ends of which are cut off at an angle so that the outer edges 23 thereof when turned inwardly will yieldingly engage the rear of the picture surface 8 for holding the locking wings in a position substantially at right angles to the back stay 21. 50 The other end 24 of the easel strip which may be of considerable width as shown in Fig. 2, is pasted to the lower end of the back of the frame and has a continuous supporting portion 25 which extends a distance below the frame with 55 a bottom cut-out portion 26 and an intermediate locking tongue 27 formed of the material of the easel strip and hinged about a score line 28 to fold rearwardly and when set up to provide a 60 simulation of an open stand having legs 29 connected by a cross piece 30. The sides of the standard 25 have hinged locking wings 31 for stiffening and for appearance, adapted to be folded rearwardly with the lower edges engaging 65 a connecting bottom 32 which extends from the lower ends of the legs 29 to the lower end of the rear supporting strut 21. Intermediate the hinged connections of this bottom support 32 is a folding score 33 which adapts the bottom to 70 be collapsed upwardly as shown in broken outline in Fig. 3, and to assume a straight base portion upon which the easel is supported, the bottom being held in this distended position by the locking tongue 27 which is bent and extended 75 rearwardly into engagement with an angular cor-

ner 34 between the bottom member and the bottom of the strut member 21. This engagement holds the locking tongue 27 in place and in order to collapse the easel it is necessary only to disengage the locking tongue 27 to move it upwardly in the direction of the broken outline as shown in Fig. 3, to move the locking wings 22 and 31 out of engagement with the picture back and the bottom 32 respectively into the planes of their respective hinged supports and to fold 10 the bottom member 32 upwardly.

Instead of a wide locking member 6 as shown in Figs. 1 to 6, the frame ends 40 may be extended as shown in Fig. 11, and a narrow central locking member 41 may be employed. This 15 locking member 41 and the frame ends may be provided with snap fastener parts 42 and 43 which separably interengage for holding the parts together, or if desired, these parts may be permanently attached by gluing, stapling, or 20 any other suitable well known manner. This form of the invention is also provided with locking tongues or projections 44, in front of which the lower edge of the frame ends 40 are inserted before they are attached to the locking member 25 41. The frame is the same in angular structure as that shown in Figs. 1 to 6 and the same easel may be applied thereto or a different type of easel, as shown more clearly in Figs. 8 and 9.

Referring now more particularly to Figs. 7 to 30 10 inclusive, a similar appearing frame structure is provided from a single sheet 50 of suitable material, in which the ends and sides forming the frames are angularly cut at the corners to provide separate folding sides 51 and ends 52. Each 35 side and end structure has parallel scores 53 and 54 for folding it over inwardly, and spaced outer tongues 55 for engaging slots 56 at the inside of the sheet for holding the frame portion in place and to define a rectangular inner picture surface 40 57 as shown more clearly in Fig. 7. The upper extremities 58 of the inwardly turned side frame portions have an angular extension which is overlapped by the inwardly turned end frame 45 portions 59 to make a tight angular fit at the 50 corners of the frame. With this construction it will be seen that the back of the frame is the back of the material forming the front picture surface 57 and the frame is a closed structure entirely in front of the marginal edge of the sheet 55 material. This makes a strong, easily folded frame structure without corner locking projections and one which may readily be formed of a single piece of sheet material. One objection to it is that the picture surface and the surface 55 forming the frame are on opposite sides of the sheet 50 before it is scored, cut and folded, which requires that printed or lithographed sheets must be applied to the opposite surfaces of the cardboard or other material forming the base 60 of the sheet material. In the form shown by Figs. 1 to 6 the frame and the picture may appear on the same printed or lithographed sheet which is applied to the front surface of the sheet material. In addition to the requirement of one 65 printed sheet only, the form shown in Figs. 1 to 6 overcomes any required precision as to registration of the designs on the printed sheets at the front and back of the sheet material which might be required in the structure of Figs. 7 to 10.

An easel as shown more clearly in Fig. 3 may be applied to the frame shown in Fig. 7, or two separate easel members 60 may be applied by means of a pasting wing 61 to the back of the 75

picture sheet 50 (or to the other sheet 1) and each of these members has a cut-out locking tongue 62 adapted to engage the hinged wing portion and to hold it at right angles to the pasting wing 61, the wings resting when turned backwardly upon the lower, slightly inclined, supporting edges 63 which are adapted to hold the display frame in a slightly inclined position.

In order to fold the easel portions with respect to the frame and to nest the frames together, these easel members 60 are preferably provided adjacent the lower edge of the picture frame with a folding crease 64 which extends entirely across the member, permitting it to fold together 15 upon itself as indicated in the broken outline in Fig. 8, and being held in its distended position by a locking wing 65 at the outer edge of the member 60 which is turned at right angles to the main portion of the supporting wing when 20 the wing is extended to hold the supporting wing against collapsing or folding about the fold line 64 until this locking wing portion 65 is again turned into the plane of the remainder of the supporting wing portion.

25 When the easels are released by the locking tongues 62 and are folded inwardly against the back of the picture frame, the lower projecting portion of the easel may be folded up about the fold line 64 against the attached back portion so 30 that when this type of easel is applied to the frame structures as shown by Figs. 1 to 6, the frames will nest together as shown more clearly in Fig. 13 so that a great many of them may be packed or supported in a more compact space and 35 relation with respect to each other.

With the construction herein disclosed it is apparent that a complete frame display is provided from a single sheet of material which very closely resembles a picture with a regular enclosing frame applied thereto and made entirely 40 of flexible sheet material. Because of the angular frame construction when it is set up, the display will have considerable rigidity and when applied to or supported by a separate or an attached easel it will have the appearance of an easel supported picture, thereby having the appearance of a high-class picture properly supported by a conventional type of easel. The entire display may be shipped or carried in substantially flat condition thereby occupying little 45 space and a number of them may be nested closely together if desired. They may be easily set up and locked in distended position when ready for use, the locking wings holding the parts in 50 distended position. The folding and collapsing of the display is easily accomplished as above set forth by simply reversing the locking and folding operations. It is not necessary ordinarily to set up the frame structure but it is easily done by the 55 engagement of the frame parts as set forth in the specification.

Various changes in the construction, combination and arrangement of the parts may be made without departing from the spirit and scope of 60 the invention.

I claim:

1. A framed picture display comprising a single sheet of material with its marginal edges cut, scored, and foldable to form an outwardly extending angularly offset marginal frame, the corners being intact and the marginal cuts being at a distance from the corners, and the adjacent sides of the cuts having disengageable interlocking hooked portions at their outer edges at an angle to each other for releasably drawing up the 75

frame portions at the sides and between adjacent corners and holding the frame in forwardly extending position.

2. A framed picture display comprising a single sheet of material scored, cut and folded to form 5 a picture plane, and a surrounding frame angular in cross section and an easel attached to the back of the picture plane portion, extending below the frame when it is set up, the easel being attached only to the back of the picture plane portion, 10 having a rectangular supporting base, and being foldable against this portion and the lower end of the easel being foldable upon itself within the confines of the frame so that a number of displays can be nested together by folding the easels 15 and leaving the frames in distended position.

3. A framed picture display having marginal edges cut, scored and foldable upon themselves and with respect to the central portion of the display to provide a picture plane surrounded on 20 four sides by a forward angularly offset marginal frame, and a supporting easel attached to the rear of the picture plane portion having a rectangular supporting base and extending below the frame to support it in distended position, the 25 easel being foldable first against the back of the framed display and then the lower portion of the easel being foldable against itself within the confines of the picture plane so that a number of displays may be nested close together in folded 30 position, the angularly offset portion of one frame being seated partially within the corresponding portion of the next adjacent displays.

4. A framed picture display comprising an extensible and collapsible marginal frame portion 35 scored, cut and folded to extend angularly forward and then rearwardly with respect to the interior of the display, a supporting easel attached to the rear of the display, and having spaced parts extending below the lower edge of the frame 40 to support the frame in a raised position, the lower extending parts of the easel representing the legs of a conventional easel and the easel having collapsing fold lines for folding it flatly against the rear of the display, and also having 45 locking flaps foldable at an angle to the easel for holding it in distended position, the frame and easel each being formed of sheet material and being each separately foldable to flat condition while attached and jointly collapsible to flat condition.

5. A framed picture display comprising sheet material cut, scored and foldable to provide a marginal frame surrounding an inner picture plane portion, the frame being transversely cut 55 at opposite sides and the adjacent edges being formed with interengaging portions for locking the frame sections together and in angularly offset relation to the picture plane portion, the end portions of the frame adjacent the corners being 60 cut at an angle to the intermediate section so that when the interengaging portions are locked together, the frame parts will be drawn inwardly about the picture plane portion, thereby causing the frame to be angularly offset.

6. A framed picture display comprising sheet material cut, scored and foldable about the edges to form an inner picture plane and a surrounding marginal frame, the frame having offset portions transversely cut to provide a locking flap 70 and the adjacent frame portions connected at the corners to the other side frame portions being disposed at an angle to the end of the sheet material from which they are cut, locking projections extending from the plane of the pic- 75

ture frame and adapted to engage the free angular adjacent ends of the picture frame in locking position, the locking flaps and the adjacent edges of the frame portions having interengaging means to draw the frame portions together in an angularly offset position about the picture plane when the said frame end portions are engaged in front of the locking projections.

7. A framed picture display comprising a single sheet of material cut, scored and foldable to form a picture plane and a surrounding raised frame angular in cross section, the frame having offset ends cut transversely thereof to form locking tabs with angular wings at the ends, and the adjacent frame portions at the ends being cut free from the picture plane and at an angle thereto, the adjacent edges of these end frame portions and the adjacent ends of the locking wings having interengaging means for drawing the frame portions together and elevating them above the plane of the picture, and the said locking wings also offsetting that portion of the locking tab which is between them from the remainder of the end of the frame.

8. A foldable frame display comprising sheet material cut, scored and foldable to form a marginal frame structure about a picture frame, the frame being transversely cut at opposite sides intermediate the corners to provide locking portions, interengaging means between the locking

portions and the adjacent frame parts for drawing the frame parts inwardly about the edge of the picture plane and providing a frame portion beveled forwardly from the picture plane and an outer edge portion inclined rearwardly from the outwardly beveled portion, the connecting angular corners of the frame portions being scored so that the frame will fold oppositely in the beveled and outer portions at the corners.

9. The combination with a picture frame display comprising a single sheet of cardboard having its marginal edges scored, cut and foldable and with interengaging opposite cut portions to draw the frame portions inwardly with respect to the picture plane, forming an angular beveled frame on all sides of the picture plane, and an easel therefor comprising a single piece of material having one end attached adjacent the top and the other end adjacent the bottom of the back of the picture display, the intermediate portion of the easel comprising a back brace and a front brace separated by a collapsible base, the back base having side locking wings engaging the rear of the display at the top to hold them in distended position, and the front support having a central cut-out tongue foldable backwardly into the angle between the base and the rear brace to hold the easel yielding in upright distended position supporting the frame display.

HENRY ZIEMMERMAN. 30
